LOCKED FAUCET

Ronald M. Wilson, Devon, Pa., assignor to William M. Wilson's Sons, Lansdale, Pa., a firm composed of Robert G. Wilson and Ronald M. Wilson

Application September 13, 1944, Serial No. 553,845

1 Claim. (Cl. 251—163)

1

My invention relates to a locked valve used to control the flow of liquid through a faucet which is opened by pressure upon an actuating lever which bears upon the exposed end of a valve stem carrying a valve seated to close the faucet by the pressure of an opposing spring, but unseated and opened by pressure applied to the exposed end of the valve stem by the actuating lever which is pivoted upon the faucet.

Such constructions have been used before, and it is not novel to protect such valve against unauthorized opening by the use of a lock (as for example a padlock) which prevents the lever from being actuated to exert pressure upon the valve stem unless the padlock is removed. But it has been found that such prior devices are capable of being tampered with notwithstanding the partial protection which has heretofore been afforded to the projecting end of the valve stem. By my invention I have accomplished a form and arrangement of the pressure lever and its opposing parts such that it is not possible without the removal of the padlock to apply pressure on the top of the valve stem to open the valve and release liquid through the faucet.

I will now describe and claim the means whereby this desirable end is accomplished.

In the accompanying drawing:

Fig. 1 is a side view partly in section of a faucet to which my invention has been applied.

Fig. 2 is a front elevation of the same.

Fig. 3 is a similar view of the same with the pressure lever removed and the stem shown in section.

In these figures, the reference numeral 1 designates the main body of a faucet which terminates in a down-turned outlet 2. The faucet contains the valve seat 3 upon which the valve 4 is seated by virtue of the pressure of the spring 5 interposed between the valve and a shoulder 6 formed in the interior of the faucet. The valve 4 has a central valve stem 7 one end of which reaches within the spring while the other end is projected through a suitable aperture 8 in the top of the outlet 2 and terminates in a rounded top 9. Upon the outlet 2 and in proximity to the projecting valve stem 7 is a large lug 10 to which is pivoted, by the pintle 11, an actuating lever 12. The faucet also carries a guide projection 13 which passes through a corresponding slot 15 in the lever 12, the shape of the projection 13 and the length of the slot 15 being such that when the lever 12 is in its uppermost position no space is left for the insertion of a tampering instrument. The pro-

2

jection 13 guides the movement of the lever 12, the side flanges 18 whereof assisting in such guidance. The end of the guide projection 13 is formed with a catch extension 14, which limits the outward throw of the lever 12. The projection 13 is also provided with an aperture 16 suitable to receive the hasp of a padlock, not shown, which when thus placed prevents depression of the lever 12; but when such padlock is removed the lever 12 may be further depressed so as to bear against the projecting end of the valve stem 7 and exert upon it sufficient pressure to oppose the spring 5 and unseat the valve 4 releasing the flow of liquid through the faucet.

The lug 10 not only receives the pintle 11 but it surrounds the aperture 8 through which the valve stem 7 passes and is there enlarged sufficiently to considerably increase the extent of the bearing of said stem in the faucet. An opposing thickening 20 of the inner wall of the faucet supplements the lug 10 so that there is provided an extensive guide surface for the valve stem 7 insuring the proper seating of the valve 4 and preventing escape of liquid around said stem where it pierces the top of the faucet. The lug 10 is projected beyond the valve stem aperture 8 and shaped to provide a raised guarding surface 17. The actuating lever 12 has its sides 30 turned down to form the flanges 18, 18 which pass with only sufficient clearance one on each side of the lug 10, and between these flanges there is formed a cross-web 19 reaching from side to side and so placed and shaped that its edge 21 when the lever 12 is in the locked position is in close proximity to the guarding surface 17 of the lug 10, the proximity of the two effectually preventing the insertion of any instrument which, if forced under said lever, 40 might be used to wrongfully push down the valve stem 7 against the valve spring 5.

It will thus be seen that by means of the catch extension 14 of the guide projection 13, the enlarged guarding surface 17 of the lug 10 and the cross-web 19 between the flanges 18 of the lever 12 a structure and combination of parts is provided which effectually encloses and protects the valve stem 7 from being depressed so long as the padlock remains in place but, upon removal 45 of the padlock, hand pressure readily operates the valve 4 permitting flow of liquid through the faucet.

Having thus described my invention, I claim: A locked faucet comprising in combination a main body having a down-turned outlet por-

tion; a spring pressed valve and projecting valve stem, respectively coactive with a seat in said body and an aperture through the wall of said outlet portion; a lug on the faucet surrounding the projecting valve stem where it extends through the outlet portion of the faucet; an actuating lever with side flanges spaced to closely flank and lap the lug; an apertured ear forming a part of the lug to which the actuating lever is pivoted below and in position to push the 10 valve stem inwards in opposition to the spring for opening the valve, and said apertured ear closing-in the pivotally connected end of said actuating lever; a guide projection on the faucet above the lug with extension through a corresponding slot in the actuating lever, said projection being provided at its free end with a

catch limiting the throw of the lever away from the projecting end of the valve stem, and the length of the lever slot being such that no clearance is afforded thereabout when the actuating lever reaches either end thereof; an aperture through the guide projection capable of receiving the hasp of a lock to restrain movement of the actuating lever to depress the valve stem; a cross-web extending between the flanges of the actuating lever; and a raised guarding surface provided on the lug extending into close proximity to the outer end of the actuating lever cross-web whereby the projecting end of the valve stem is surroundingly closed-in and made positively inaccessible when said lever is in locked position.

RONALD M. WILSON.
